BLOUSE WITH VARIABLE NECKLINE
EFFECT

Felicia Alberich, Sunnyside, N. Y.

Application January 23, 1948, Serial No. 3,913

5 Claims. (Cl. 2—106)

1

This invention relates to new and useful improvements in women's apparel, and, more particularly, aims to provide a novel and valuable upper garment, as one of the blouse or pull-over sweater type, so formed that any one of a multiplicity of pleasing arrangements can be made, at the will and according to the flair of the wearer for decorative originality, merely by differently draping the front upper portion of the garment.

The new garment can be made to be worn as a blouse, sweater or other bodice unit, with the lower portion thereof inside or outside the skirt; or otherwise constituted, as will later be pointed out.

By the invention a garment is provided which may be readily modified, adjacent or below the neckline, just preparatory to or immediately after being donned, to vary the neckline and then present various ruffle effects, fold effects, flap effects and other fashionable formations, as by the aid of temporarily applied pins or clasps, such, for instance, as one or more pieces of costume jewelry.

According to the invention, essentially, a garment is so made that centrally of the sleeve openings there is provided a neck opening characterized by a nape of the neck engaging smaller portion at the back of the garment and by a very much larger portion at the front of the garment. As a result, the garment has a bust overlying exceedingly full frontal portion which is variously drapable and otherwise arrangeable pursuant to the invention. The number of widely different decorative arrangements of this full frontal portion is without limit, as will be made plain hereinafter. For purposes of illustration, a garment will be shown and described which is in the form of a sleeveless blouse made from two cut pieces of material, and in that connection some of the possible different decorative arrangements thereof will be explained; but, as will be understood, the invention is not to be thus limited.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 shows the piece of material to form the front of the garment, with this piece cut to include marginal portions, as indicated in dot and dash lines, for being folded over and in certain

2

cases stitched in place as also indicated in this view, preparatory to stitching together said piece and the complementary piece to form the back of the garment.

5 Fig. 2 is a view similar to Fig. 1, showing the piece last mentioned.

Fig. 3 side elevationally shows the garment made from the pieces of material illustrated in Figs. 1 and 2, on the body of a woman, with the 10 full upper portion of the piece of Fig. 1 drawn forwardly to its maximum limit of distention without stretching the material.

Fig. 4 is a top plan view of the garment as arranged in Fig. 3 as such garment would otherwise conform itself to the female figure.

Figs. 5 through 14 are all like views, each showing in frontal perspective the garment on the body portion of a headless manikin, but each showing one of some of the many possible decorative arrangements aforesaid.

Referring to the drawings more in detail, the garment illustrated comprises a front section 20 and a back section 21.

The front section 20, when finished, is approximately of T-outline, having a top edge 22 which may be straight. Beyond each end of said top edge is a substantially triangular lateral extension 23 bounded by an upper outwardly downwardly inclined edge 24 and a lower downwardly inwardly inclined edge 25. Near their lower limits said edges 25 merge with the preferably slightly curvilinearly extending upper portions 26 of lower side edges 27 joined at their lower ends by a bottom edge 28 which, substantially paralleling the top edge 22, may also be straight.

As in this instance shown, the T-form of the front section 20 may be said to be made up of a staff portion bounded by the top edge 22, the lower substantially straight portions of the side edges 27 and upward prolongations of the latter toward said top edge; with the bar of the T established by and between the lateral extensions 23. As will also be noted, the maximum width of the section 20 is greater than its maximum height.

Preparatory to seaming the front section 20 with the rear section 21, the section 20 is desirably cut to provide marginal portions as shown in dot and dash lines, to be folded over as illustrated at 29, 30, 31, 31 and 32; the preferred stitching, to anchor some only of these to the main portion of the section, being indicated at 33.

The rear section 21, while also presenting near its top oppositely extending triangular side extensions 34, is approximately of generally rectan-

gular shape, of about the same height as maximum width, but somewhat greater in height than in width if the side extensions be disregarded.

Said section 21 has a top edge 35, desirably slightly downwardly arched, this to form the part of the neck opening in the completed garment to engage the nape of the neck of the wearer, and very much shorter than the top edge 22 of the section 20. Descending from the opposite ends of said top edge 35 are the upper edges 36 of said side extensions 34, the lower edges of said extensions being designated 37. Below the side extensions 34 are opposite side edges 38, joined at their lower end by a bottom edge 39, which is shown as straight.

Preparatory to seaming this back section 21 with the front section 20, the section 21 is also desirably cut to provide marginal portions as shown in dot and dash lines, to be folded over as illustrated at 40, 41, 41, 42, 42 and 43; the preferred stitchings, to anchor some only of these to the main portion of the section, being indicated at 44.

The two sections 20 and 21 are suitably stitched together, to complete the garment, viz: The edge 24 at each side of the section 20 to an edge 36 of the section 21, to form inside shoulder seams as indicated at 45 in Figs. 3 and 4, and the lower side edge 26—27 at each side of the section 20 to a lower side edge 38 of the section 21, to form two inside side seams as indicated at 46 in Fig. 3, thereby to provide arm openings 47. As will be understood, the edges 24, 25 and 26—27 of the section 20 are of the same lengths, respectively, as the edges 36, 37 and 38 of the section 21.

Before the front upper fullness of the garment, which fullness may be called its low hanging drape, is arranged in any of the ways possible, such, for instance, as variously shown in Figs. 5 through 14, an extremely large neck opening 22—35 is present, making the garment a pull-over one.

In Fig. 5 an arrangement to give a very low V-neck is shown as effected by the use of a single pin or clasp 48.

In Fig. 6 a medium low ruffled or jabot effect is shown as established by the use of one or more pins or clasps now hidden.

In Fig. 7 a collarette effect atop a slenderized deep V opening is shown as obtained by the use of a pin or clasp 49 applied high up on the garment, with at the bottom of such V, a side splay of the garment material held in place by one or more pins or clasps now hidden.

In Fig. 8 is illustrated an arrangement to give a high neck line above a central pleating, achieved by the aid of a pin or clasp 50.

Fig. 9 shows a very low and wide neck front attended by ruffle lines running around the front and sides of the neck and held in place by two pins or clasps 51.

In Fig. 10 is shown a high neck opening with the garment material folded into a fairly large flap 52' converging to a side point and toward one shoulder reefer-fashion, effected by the aid of a pair of pins or clasps 52.

Fig. 11 illustrates again a high neck opening, with oppositely located portions of the garment material, each folded into a flap 53' directed toward the center of the body and converging at the neck, and there held by the aid of a pin or clasp 53.

In Fig. 12 is shown a medium and fairly high neck line, the front of which is marked by a horizontal line 54', with below such line a squared

drape resembling the top of a high apron, effected by the aid of a pair of pins or clasps 54.

In Fig. 13 is illustrated a high neck line, below which are ruffles 55' partially at the front of the garment, but mainly toward one shoulder, this effected by the aid of a pin or clasp 55.

In Fig. 14 is shown another high neck line, below which are two sets of ruffles 56', established by the aid of two pins or clasps 56.

10 A multitude of other easily made and equally strikingly attractive variations, each providing a garment which appears to the onlooker to be a separate wardrobe piece, could be illustrated.

As will be understood, the usual or any desired shoulder pads, such as those indicated at 57 in Fig. 4, may be used with the garment; also, the garment may be provided with sleeves of any length and/or with other additions, such, for instance, as decorative adjuncts at the neck line or 20 elsewhere; also, the bodice member may be part of a single garment having a permanently incorporated skirt.

It is to be understood that this neck arrangement may be used in any garment such as blouse, 25 sweater, etc.

While I have illustrated and described the preferred embodiments of my invention, it is to be understood that I do not limit myself to the precise constructions herein disclosed and the right 30 is reserved to all changes and modifications coming within the scope of the invention as defined in the appended claims.

Having thus described my invention, what I 35 claim as new, and desire to secure by United States Letters Patent is:

1. A pull-over garment incorporating a peripherally continuous neck opening including a rear portion for lying against the nape of the back of the wearer and a front portion which is of a 40 length several times that of said rear portion, said garment including a front section substantially T-shaped in outline with the ends of the cross-bar of the T substantially triangular, said bar-ends having outwardly downwardly sloping upper edges and inwardly downwardly sloping bottom edges, and said front section having a substantially straight top edge joining said outwardly downwardly sloping edges, which top edge provides said longer portion of said neck opening.

2. A pull-over garment incorporating a peripherally continuous neck opening including a rear portion for lying against the nape of the back of the wearer and a front portion which is of a 45 length several times that of said rear portion, said garment including a front section substantially T-shaped in outline with the ends of the cross-bar of the T substantially triangular, said bar-ends having outwardly downwardly sloping upper edges and inwardly downwardly sloping bottom edges, and said front section having a substantially straight top edge joining said outwardly downwardly sloping edges, which top edge provides

50 said longer portion of said neck opening, said garment also including a rear section which near its top has laterally extending projections having outwardly downwardly sloping top edges and inwardly downwardly sloping bottom edges, said rear section having a top edge joining its said outwardly downwardly sloping edges, which top edge provides

55 said longer portion of said neck opening, said garment also including a rear section which near its top has laterally extending projections having outwardly downwardly sloping top edges and inwardly downwardly sloping bottom edges, said rear section having a top edge joining its said outwardly downwardly sloping edges, which top edge provides

60 said longer portion of said neck opening, said garment also including a rear section which near its top has laterally extending projections having outwardly downwardly sloping top edges and inwardly downwardly sloping bottom edges, said rear section having a top edge joining its said outwardly downwardly sloping edges, which top edge provides

65 said longer portion of said neck opening, said front section having a maximum width greater than its maximum height.

3. A pull-over garment incorporating a peripherally continuous neck opening including a rear

portion for lying against the nape of the back of the wearer and a front portion which is of a length several times that of said rear portion, said garment including a front section substantially T-shaped in outline with the ends of the cross-bar of the T substantially triangular, said bar-ends having outwardly downwardly sloping upper edges and inwardly downwardly sloping bottom edges, and said front section having a substantially straight top edge joining said outwardly downwardly sloping edges, which top edge provides said longer portion of said neck opening, said garment also including a rear section which near its top has laterally extending projections having outwardly downwardly sloping top edges and inwardly downwardly sloping bottom edges, said rear section having a top edge joining its said outwardly downwardly sloping edges, which top edge provides said shorter portion of said neck opening, said front section having a maximum width greater than its maximum height, and said rear section having a maximum height substantially equal to its maximum width.

4. A pull-over garment incorporating a peripherally continuous neck opening including a rear portion for lying against the nape of the back of the wearer and a front portion which is of a length several times that of said rear portion, said garment including a front section substantially T-shaped in outline with the ends of the cross-bar of the T substantially triangular, said bar-ends having outwardly downwardly sloping upper edges and inwardly downwardly sloping bottom edges, and said front section having a substantially straight top edge joining said outwardly downwardly sloping edges, which top edge provides said longer portion of said neck opening, said garment also including a rear section which near its top has laterally extending projections having outwardly downwardly sloping top edges and inwardly downwardly sloping bottom edges, said rear section having a top edge joining its said outwardly downwardly sloping edges, which top edge provides said shorter portion of said neck opening, said front section having a maximum width greater than its maximum height, and rear section having a maximum

height substantially equal to its maximum width, said top edge of the rear section being downwardly arched.

5. A pull-over garment incorporating a peripherally continuous neck opening including a rear portion for lying against the nape of the back of the wearer and a front portion which is of a length several times that of said rear portion, said garment including a front section substantially T-shaped in outline with the ends of the cross-bar of the T substantially triangular, said bar-ends having outwardly downwardly sloping upper edges and inwardly downwardly sloping bottom edges, and said front section having a substantially straight top edge joining said outwardly downwardly sloping edges, which top edge provides said longer portion of said neck opening, said garment also including a rear section which near its top has laterally extending projections having outwardly downwardly sloping top edges and inwardly downwardly sloping bottom edges, said rear section having a top edge joining its said outwardly downwardly sloping edges, which top edge provides said shorter portion of said neck opening, said front section having a maximum width greater than its maximum height, and said rear section having a maximum height substantially equal to its maximum width.
